UNITED STATES PATENT OFFICE.

JOHN W. GODBEHERE, OF HOT SPRINGS NATIONAL PARK, ARKANSAS.

UNION SUIT.

Application filed March 17, 1923. Serial No. 625,875.

To all whom it may concern:

Be it known that I, JOHN W. GODBEHERE, a citizen of the United States, residing at Hot Springs National Park, in the county of Garland and State of Arkansas, have invented certain new and useful Improvements in Union Suits, of which the following is a specification.

My invention relates to an improvement in union suits for men, women and children.

The object is to provide an article as the name implies, of such construction that it gives readily with the bending of the body without severe strain which ordinarily results in pulling off buttons or tearing off button holes if not actually ripping or tearing the garment.

This invention includes a garment having a drop seat, the upper edge of which is supported, adjusted, held in position and fastened by bands that go around the waist and button in front, thus giving the garment plenty of play without binding upon the body, in other words, automatically adjusting itself to the body.

In the accompanying drawings, Fig. 1 is a view in perspective, and Figs. 2 and 3 are details.

A represents a garment and 1 the drop seat, the latter extending from the lower ends of the side slits 2 approximately to the region of the waist-line somewhat overlapping the lower edge 3 of the back 4 of the garment, with a binding 5 preferably at the upper edge of the drop seat.

Bands and preferably double bands 6 and 7 extend from opposite ends of this binding 5 through loops 8 at the side seams of the garment through which they have loose sliding movement giving play and freedom of action, and they terminate in pads 9 and 10, one of which is provided with a button 11

and the other with several button holes 12 of which three are shown whereby to adjust it the size of the waist and easily secure the 45 ends of the bands detachably together.

By the double bands a stop is formed to prevent the bands from pulling out when the drop seat is lowered as might otherwise happen, especially where the bands do not 50 have to be very long for either a child or a slender person.

This leaves a smooth buttonless drop seat easily raised or lowered and which can be drawn about the waist just as tight as required and a single button at the front holds it in place in cooperation with the loops and the double straps slidably therethrough.

In this way the garment adjusts itself automatically to the movements of the body 60 and in stooping down the side pieces allow plenty of play so that there is no strain on the garment as there usually is on garments that are now on the market.

The garment is easily made, is of few 65 parts and is comfortable to wear and easy and simple to operate and adjust, and in this form obviates in a simple way peculiar garments of this general type hitherto in use.

I claim:

An undergarment having a drop seat, double loops fastened to the sides of the garment, and double bands extending from the upper portion of the drop seat slidably through the loops to the front of the garment, the front free ends of the bands being connected by pads which carry means for fastening the two double bands together, said pads also serving as stops for preventing the bands from being pulled entirely 80 through the double loops.

In testimony whereof I affix my signature.

JOHN W. GODBEHERE.
